SEGREGATION ELIMINATOR

Earl E. Starner and Charles M. Mitchell, Dresden, Ohio, assignors to The Zanesville Gravel Company, Dresden, Ohio, a corporation of Ohio

Application July 26, 1941, Serial No. 404,249

2 Claims. (Cl. 259—180)

This invention relates to new and useful improvements in means for preventing the segregation of fine and coarse gravel and other granular material in the charging of hoppers and other dispensing receptors.

The principal object of the present invention is to provide an eliminator which can readily be installed in hoppers and which in use will regulate the mixing of coarse and fine particles at the bottom of the hopper.

Other objects and advantages of the invention will become apparent to the reader of the following specification.

In the drawings:

Figure 1 represents a side elevational view of a 15 single type hopper equipped with the present invention.

Figure 2 is a top plan view of the structure shown in Figure 1.

Figure 3 is a vertical sectional view taken substantially on the line 3—3 of Figure 2.

Figure 4 is a top plan view of a double type hopper.

Figure 5 is an enlarged sectional view taken substantially on the line 5—5 of Figure 4.

Referring to the drawings wherein like numerals designate like parts, it can be seen in Figures 1, 2 and 3 that numeral 5 denotes a downwardly tapering hopper having a restricted bottom 6. In this bottom is a discharge opening 7 over which a manually operative gate 8 is disposed, this gate being provided with an external shank 9 equipped with a handle 10. Numeral 11 denotes a conveyor for conveying gravel or other granular material to the hopper.

Figures 4 and 5 disclose a double type hopper which, of course, consists of a shell 5a having a bottom 6a in which are discharge openings 7a, 7a over which gates 8a, 8a are disposed, these gates having shanks 9a and handles 10a. In this form of hopper a vertical transverse partition 12 is provided for dividing the interior of the hopper into compartments 13 and 14.

The present invention which is generally referred to by numeral 15 can be placed in the single compartment of the hopper 5 as shown in Figures 2 and 3 or in each of the compartments 13 and 14 of a double or multiple type hopper.

The present invention consists of a pan 16 supported upon horizontally disposed straps 17 which are suitably secured at their ends to side walls of the hopper 5 or 5a. The central portion of this pan 16 which has sloping side walls 18 is formed with a circular or desirably shaped opening 19 under which is a gate 20 operative 55

in a box 21 suitably secured to the bottom side of the pan 16.

A shank 22 extends from the gate 20 and through an opening in a side wall portion of the hopper, this shank being equipped with a handle 23.

It can now be seen that the gate 20 can be regulated to the desired position so that only a certain amount of material which comes to rest upon the pan 16 can pass therethrough to the bottom of the hopper. In charging hoppers with gravel, for instance, it has long been realized that as the gravel drops into the hopper the finer particles drop almost vertically while the coarser particles describe an arc and in this way segregate from the finer particles, with the result that the coarser particles will back up along one side of the hopper while a cone of finer gravel will form from the bottom up, with the result that when the gate 8 or 8a is opened for the discharge of material an unsatisfactory size of gravel is dispensed.

In the present invention the finer gravel forms a mass upwardly from the pan 16 while the coarser gravel has a chance to pass around the pan, the gate 20 being regulated so as to permit only a certain amount of the finer material to pass downwardly thus affording at all times a uniform and desirable mixing of the fine and coarse particles at the bottom of the hopper.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. An apparatus for preventing the segregation of fine and coarse granular material in a hopper having a discharge outlet at its bottom, comprising a pan centrally mounted in the hopper in spaced relation from the outlet, said pan being spaced from side walls of the hopper, said pan having a controllable orifice therein for the regulated passage of material therethrough and means for depositing the material into the top of the hopper at substantially the central portion thereof, whereby the fine material will drop into the pan and some of the coarser material will pass into the hopper between the space formed by the pan and the adjacent side walls of the hopper.

2. An apparatus for preventing the segregation of fine and coarse granular material in a

hopper having a discharge outlet at its bottom, comprising a pan centrally mounted in the hopper above the outlet, said pan being spaced from side walls of the hopper, said pan being provided with sloping side walls and having an opening in the bottom thereof, a gate for closing the opening in the pan, a shank extending from the gate to a point exteriorly of the hopper and means for depositing the material into the top of

5 the hopper at substantially the central portion thereof, whereby the fine material will drop into the pan and some of the coarser material will pass into the hopper between the space formed by the pan and the adjacent side walls of the hopper.

EARL E. STARNER.
CHARLES M. MITCHELL.
